Application June 13, 1930, Serial No. 461,020

3 Claims. (Cl. 178—44)

This invention relates to tuned circuits and particularly to tuned circuits for use in radio frequency or carrier wave transmission systems.

An object of the invention is to provide coupled circuits that exhibit selectivity and transmission characteristics throughout the entire range of frequencies over which they may be tuned. A further object is to provide a system of tuned circuits having fixed coupling units between the circuits; the units being so chosen that the coupling between the tuned circuits may be maintained approximately constant throughout the tuning range. More specifically, an object is to provide a tuning system including two capacitively coupled circuits which may be continuously tuned to resonate at the same frequency, the coupling between the tuned circuits including series and shunt capacities of such values that the variation, with frequency, of the total coupling between the tuned circuits is substantially reduced.

These and other objects of the invention will be apparent from the following specification when taken with the accompanying drawings, in which,

Fig. 1 is a circuit diagram showing one embodiment of the invention employed as a coupling between a collector system and a carrier wave amplifier,

Fig. 2 is a circuit diagram illustrating the invention as embodied in an interstage coupling,

Fig. 3 is a curve sheet showing the variation, with frequency, of the coupling coefficients and of the power ratio of the coupling circuits,

Figs. 4, 5 and 6 are curve sheets showing frequency-gain characteristics for circuits such as shown in Figs. 1 and 2, respectively, and

Fig. 7 is a curve sheet showing graphically the relation between frequency and selectivity in coupled circuits embodying the invention.

As shown in Fig. 1, the invention is embodied in an input system for use between a collector system A, G, and the first tube T of a carrier wave amplifier.

The tuned input system comprises substantially identical LC circuits in which the high potential terminals of the adjustable condenser C and fixed inductance L of the separate tuned circuits are connected, respectively, to the antenna A through a coupling condenser C₀, and to the control grid G₁ of the tube T. The low potential terminals of the condensers C are connected to each other and to ground, and the low potential terminals of the inductances L are joined and are connected to ground through the coupling condenser C_m. For feeding a direct cur-

rent bias to the control grid, the condenser C_m may be shunted by a fixed resistor R₁.

In addition to the coupling condenser C_m, the tuned circuits are coupled by a second capacity C_{m'} between the high potential ends of the tuned circuits. For convenience of description the coupling capacities C_m and C_{m'} will be referred to as shunt and series couplings, respectively, since they bear these relations to the general direction of transmission along the collector-amplifier system.

The two LC circuits are preferably provided with a common adjusting means, such as indicated diagrammatically by dial D and shaft S, to secure simultaneous adjustment of the circuits to resonance at the same frequency.

As shown in Fig. 2, substantially the same arrangement as above described may be employed as an interstage coupling between successive tubes T, T', of a multistage amplifier. For such use, the inductance L of the first tuned circuit preferably forms the secondary of a transformer which has as its primary winding the plate inductance L₁ of the tube T.

For simplicity, the circuit diagrams constituting Figs. 1 and 2 do not illustrate the sources of plate current supply and the cathode-heating circuits, but it will be understood that the usual or any desired systems may be employed for energizing the amplifier tubes.

The coupling between the tuned circuits includes both series and shunt capacitive couplings but magnetic coupling is substantially zero. At the higher frequencies the effects of the series coupling C_{m'} predominate and at the lower frequencies the effects of the shunt coupling C_m are the more pronounced. The values of the coupling capacities are preferably so chosen as to give less than critical coupling between the two tuned circuits throughout their entire tuning range, i. e., at any adjustment of the tuning condensers the transmission along the system is a maximum for but one frequency and not for two slightly separated frequencies. To accomplish this result, the maximum value of the coupling due to shunt capacity C_m must be somewhat below the amount necessary to produce critical coupling at the low frequency end of the tuning range, and the maximum value of the coupling due to the series capacity C_{m'} must be somewhat less than the amount necessary to produce critical coupling at the high frequency end of the tuning range.

If the coefficients of coupling between the circuits due to C_m and C_{m'} are represented by k and

k' , respectively, their values are given very closely by the equations:

$$5 \quad k = \frac{C}{C_m}$$

$$k' = \frac{C_m'}{C}$$

where C is the tuning capacity in each circuit. Then K the total coefficient of coupling between the circuits is:

$$K = k + k' = \frac{C}{C_m} + \frac{C_m'}{C}$$

and, since

$$15 \quad C = \frac{1}{\omega^2 L}$$

$$K = \frac{1}{\omega^2 L C_m} + \frac{C_m' \omega^2 L}{1}$$

20 The frequency variation of the several coupling coefficients, k , k' and K is shown graphically in Fig. 3 by the curves identified by these reference characters. The curve P of this curve sheet shows the relation between frequency and the power ratio,

$$\frac{R}{\omega L}$$

30 of coil L of one of the tuned circuits. In this particular case, the coils L were identical and comprised single layer solenoid such as commonly employed in broadcast receivers.

35 It will be noted that the graph K for the coefficient of total coupling has approximately the same shape as the graph P for the power ratio of either inductance. In the more general case where the power ratios of the two coupled circuits are not substantially equal, the quantity, P , to which the total coefficient of coupling, K , is to be referred is given by the geometric mean 40 of the power ratios of the separate tuned circuits, i. e., by the square root of the product of the individual power ratios. Whether in the general case, or in the special case in which the tuned 45 circuits are substantially identical, the coupling between the circuits will be less than critical for all frequencies at which the coupling coefficient K is less than the quantity P . For the particular circuits or coupling system from which the data for Fig. 3 was obtained, the coupling was 50 less than critical throughout the entire tuning range since curve K does not rise above curve P at any point.

55 The invention is not restricted to circuit arrangements in which the coupling is less than critical but provides a general method of coupling circuits in such a way as to give a desired gain versus frequency characteristic. If desired, the coupling may be more or less than critical at one part of the frequency range and may 60 approach or pass beyond the critical value at another portion or portions of the range. For some purposes, such as, for example, in cascaded amplifiers, it is usually preferable to employ less than critical coupling as the alining of the gang condensers is facilitated when each stage or coupling system is resonant at but one frequency. As will be explained hereinafter, it is not necessary to employ band-pass circuits, i. e., circuits 65 coupled with more than critical coupling, to prevent "cutting of the side bands", when the coupling system is designed in accordance with the present invention.

70 As illustrative of the control over the gain-frequency characteristics which is made possible by this invention, attention is directed to Figs.

4, 5 and 6 which show the relation between frequency and voltage step-up in certain particular embodiments of the invention. In both the input and the interstage coupling systems, the several inductances L had the same value of approximately 5 220 microhenries and took the form of 100 turns of No. 30 enameled wire closely wound on a $1\frac{1}{4}$ inch tube. The adjustable condensers C were units of a gang condenser and had such 10 value that the system could be tuned over the broadcast range of from 500 to 1500 kilocycles. In the interstage coupling, the plate inductance L_1 consisted of 50 turns of No. 36 double silk covered wire wound, turn for turn, over inductance L beginning at the low potential end thereof. 15

15 In Fig. 4, the curves A, B and C show the relationship of voltage amplification and frequency for different values of the antenna coupling, which in the circuit of Fig. 1 was a capacitive 20 coupling provided by the condenser C_0 , the shunt coupling capacity being .02 microfarad and the series capacity being 0.4 micromicrofarad. The antenna capacity was 230 micromicrofarads and curves A, B and C were plotted from data obtained when the coupling condenser C_0 had values 25 of 5, 10 and 20 micromicrofarads, respectively. By "voltage amplification" is meant the ratio of the voltage impressed upon the grid-cathode terminals of tube T to the voltage induced in the antenna or collector system. It is to be noted 30 that for each value of the condenser C_0 , the voltage step-up remained approximately constant for frequencies above about 900 kilocycles. Since the usual antenna input circuits exhibit decidedly 35 higher gains at the higher frequency, it is evident that the invention provides a system which is particularly useful when uniform gain at the high frequency end of a wave band is desired. The same control of the gain-frequency characteristic obtains if the capacitive coupling to the 40 antenna is replaced by a magnetic coupling.

45 The effect obtained with different values of the series coupling C_m' will be apparent from a consideration of the curves of Fig. 5. The solid line 50 curve D represents the operation of the Fig. 2 circuit when the shunt capacity C_m was .03 microfarad and the series coupling between the tuned circuits was omitted, i. e., C_m' is equal to zero. The drop in amplification E/E_0 at the higher frequencies is very pronounced. When 55 series coupling is introduced, the amplification curve remains substantially unchanged at the lower frequencies, i. e., up to about 1100 kilocycles for the circuit elements as stated above, but dotted curves E, F and G show the increased gain at higher frequencies when the series condenser C_m' had values of 0.2, 0.4 and 0.6 micromicrofarad, respectively.

60 The curves of Fig. 6 show the relation between 60 amplification and frequency for different values of the shunt capacity C_m in the circuit of Fig. 2. Curve F is identical with curve F of Fig. 4 and represents the operation of the coupled tuned circuits for a series capacity of 0.4 micromicrofarad and shunt capacity of .03 microfarad. Curves H, 65 I, L are similar curves as obtained when the shunt capacity had values of .02, .04 and .05 microfarad, respectively.

70 The curves of Fig. 7 afford a comparison between the selectivity of one particular embodiment of the invention and the selectivity of the conventional amplifier system employing two cascaded stages having tuned output circuits. The data for the curves was obtained by tuning 75 the amplifiers to resonance at each of three dif-

ferent frequencies and measuring the gain at the resonant frequency and also at frequencies differing from that to which the amplifier was tuned. The solid line curves 600, 1000 and 1333, show the 5 selectivity, for resonant frequencies of 600, 1000 and 1333 kilocycles, respectively, of the amplifier circuit of Fig. 2 when the series and shunt capacities had values of 0.4 micromicrofarad and .03 microfarad, respectively.

10 The dotted line curves 600, 1000 and 1333 are similar selectivity curves for the conventional amplifier arrangement employing but one tuned circuit in each of two cascaded stages. These 15 dotted line curves are typical of the known tuned amplifiers and show a marked decrease in selectivity at the higher frequencies. The invention provides a more uniform selectivity throughout the frequency band over which a transmission system may be operated.

15 It is particularly to be noted that the selectivity curves representing the operation of one embodiment of the invention substantially coincide for a zone of approximately three kilocycles off of resonance. The significance of this feature is that it is possible to design a receiver system which, without the use of band pass tuners will reproduce the modulation frequencies at their proper values. All of the frequencies lying 20 in the side bands of a modulated signal are not amplified at the same rate, in the radio frequency amplifier, but the audio amplifier may be designed to correct for this differential amplification. Such a corrective audio amplifier system 25 could not be employed with the known types of radio frequency amplifiers since, as shown by the dotted line selectivity curves, the suppression of the higher audio frequencies is not constant for 30 all signal frequencies.

35 As shown by the several curves of Figs. 5 and 6, the particular values stated above were chosen to secure an approximately uniform gain at the higher frequencies. It is possible to secure even higher gains at the higher frequencies by increasing the value of the series coupling. For radio 40 reception and for other uses where high selectivity over a wide band of frequencies is desirable, the choice of the series coupling capacity is dependent, in part at least, upon the maximum step-up which is consistent with high selectivity. 45 There is considerable choice as to the relative values of the series and shunt couplings and, within those ranges which give improved selectivity characteristics it is possible to select values 50 which give a desired transmission-frequency 55 characteristic.

60 The invention is not limited, however, to a particular range of relative values of the two couplings but affords a general method for the design of tuned circuits and/or tuned amplifiers 65 which are to exhibit predetermined transmission-frequency characteristics.

It will be understood that the coupling capacity C_m' , Figs. 1 and 2, may be provided either 70 by a separate, physical condenser, or by stray coupling between the high potential ends of physical elements of the two tuned circuits, such stray coupling being produced in a manner so well known to those skilled in the art as to render unnecessary any further explanation.

75 While the invention has been described in connection with certain embodiments that are particularly adapted for the reception of broadcast signals within the 500-1500 kilocycle band, it will be apparent that the invention is equally

applicable to other frequency bands. Furthermore, at other frequency bands or when other gain-frequency characteristics are desired, it becomes practical to employ inductive couplings in place of the capacitive couplings, or to employ 5 combination inductive-capacitive couplings for either or both the series and shunt coupling elements.

I claim:

1. A tuned input circuit for a radio frequency 10 amplifier, comprising an inductance having one terminal connected to the control grid of the amplifier, a coupling condenser connected between the other terminal of said inductance and the cathode, a tuning condenser connected between control grid and cathode, a second inductance substantially identical with and having substantially zero electromagnetic coupling to said first inductance, a coupling capacity between the grid terminal of said first inductance and one 15 terminal of said second inductance, the other terminals of said inductances being directly connected together as regards direct current, a second tuning condenser connected across the non-common terminals of said coupling condenser 20 and said second inductance, a resistance connected in shunt across the coupling condenser, and means for impressing a signal upon the circuit comprising said second inductance and said 25 second tuning condenser. 30

2. In combination with a source of signal energy and an amplifier circuit, a tunable band pass network comprising a pair of tunable circuits having a common condenser included therein, means for tuning said circuits to a desired 35 frequency of a signal frequency range, the magnetic coupling between the circuits being substantially zero, and a condenser in series between the high potential sides of said circuits, the capacities of the condensers being of magnitudes such that the maximum value of the coupling due to the common condenser is below the amount necessary to produce critical coupling at the low frequency end of the tuning range, and the maximum value of the coupling due to the 40 series condenser is less than the amount necessary to produce critical coupling at the high frequency end of the tuning range. 45

3. The combination with two inductances, serially connected as regards direct current, having substantially zero electromagnetic coupling, of a capacitive coupling between the non-common ends of said inductances, a condenser having one terminal connected to the common junction 50 of said inductances, a pair of tuning condensers having a common terminal connected to the other terminal of said first condenser, the opposite terminals of said tuning condensers being connected to the respective non-common terminals 55 of said inductances, a resistance connected in shunt across said first condenser, and mechanical means connecting the adjustable elements of said tuning condensers to insure their simultaneous adjustment, the tuning condensers and inductances having such values that the two tuned 60 circuits remain continuously in resonance throughout the range of adjustment of said tuning condensers, and the total coupling provided by said capacitive coupling and said first condenser being, throughout the range of adjustment of said tuning condensers, less than critical 65 coupling. 70
